UNITED STATES PATENT OFFICE.

WILLIAM HAMMOND, OF WARREN, PENNSYLVANIA, ASSIGNOR TO HAMMOND IRON WORKS, OF WARREN, PENNSYLVANIA, A CORPORATION OF PENNSYLVANIA.

PULP-AGITATOR.

1,026,578.

Specification of Letters Patent. Patented May 14, 1912.

Application filed October 18, 1911. Serial No. 654,488.

To all whom it may concern:

Be it known that I, WILLIAM HAMMOND, a citizen of the United States, residing at Warren, county of Warren, and State of Pennsylvania, have invented certain new and useful Improvements in Pulp-Agitators; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in pulp agitators of the class set forth in Patents Nos. 923,571, 940,612 and 1,000,689, being dated June 1st, 1909, November 16, 1909, and August 15, 1911, respectively.

20 My present improvement relates more particularly to what I term cross agitation, consisting in delivering jets of liquid into the pulp as it issues from the top of the standpipe, and also delivering jets of liquid into 25 the pulp from the standpipe at intermediate points between its upper and lower extremities, whereby a more perfect agitation is obtained, the same extending over the entire cross sectional area of the agitation tank 30 and serving to thoroughly separate the particles of material from each other, whereby the metallic values are brought into such intimate relation with the dissolving solution, as a solution of cyanid of potassium, that 35 an ideal result of the character sought is obtained. In other respects, the operation of the apparatus is substantially the same, at least in a general way, as set forth in the aforesaid patents, and hence the construction and operation of the entire apparatus will not be set forth in this application in extreme detail.

The apparatus, in its entirety, consists of a tank preferably cylindrical in shape, its axis occupying a vertical position. Within this tank is centrally suspended an open ended standpipe, into which the pulp drawn from an annular chamber in the upper part of the tank is introduced through the instrumentalities of a rotary pump or other suitable means, the pulp so introduced being discharged at the top of the tank, thus forming, in a general way, a circulation of the pulp lengthwise of the tank, or in a vertical 50 direction.

It is assumed that the tank is originally filled from the top or otherwise and that the agitation of the charge, where the tank is used as a single unit, is continued until the precious metallic values have been 60 thoroughly dissolved, after which the solid matter is allowed to settle in the bottom of the tank, the clear solution, containing the metallic values, being drawn off, the said values being subsequently separated from 65 the dissolving solution by any suitable form of precipitation. This step, however, does not concern the present invention, which relates purely to features for producing a more nearly perfect agitation of the pulp, as here- 70 tofore indicated, and to this end there is arranged above the top of the standpipe a perforated section of pipe preferably arranged in the form of a horizontal coil, which is connected by means of a pipe ex- 75 tending outside of the tank with the conduit through which the pulp is carried to the lower extremity of the standpipe, the outside pipe being relatively small and controlled by a valve, whereby only a compa- 80 ratively small portion of the pulp or solution is delivered to the perforated coil in the upper part of the tank. Sprays or jets of liquid from this perforated pipe are de- 85 livered into the pulp as it issues from the top of the standpipe and is carried outwardly in all directions in sheeted form, due to the location of a baffle-plate directly above the top of the standpipe and of such area as to produce the aforesaid result. Inter- 90 mediate the extremities of the standpipe, provision is made for introducing jets of liquid from the contents of the standpipe into the pulp as it naturally passes downwardly from the top of the standpipe, the 95 said jets issuing through comparatively small openings formed in rings applied to the standpipe and so arranged that the said openings in the rings are normally closed, due to the fact that movable sections of the 100 standpipe are in their lowermost position, whereby the said sections are in actual contact with each other. These rings are secured in each case to the upper or movable section of the standpipe, the rings being so 105 connected with the lower section that the rings may move with the upper section, while the lower section remains stationary, thus opening a joint between the adjacent sections of the standpipe, which is in regis- 110

ter with exit openings formed in the said ring, whereby, as soon as the section or sections of the standpipe are raised to their limit of movement, jets of solution will issue from the standpipe intermediate its extremities for the purpose aforesaid.

Having briefly outlined my improved construction, I will proceed to describe the same in detail, reference being made to the 10 accompanying drawing, in which is illustrated an embodiment thereof.

In this drawing:—Figure 1 is a vertical section, taken through an agitating apparatus equipped with my improvements.

15 Fig. 2 is a fragmentary vertical section of the standpipe, taken through one of the joints formed for the purpose of introducing intermediate sprays or jets of solution from the standpipe intermediate its extremities.

20 In this view, the upper section of the pipe has been raised to open communication between the interior of the pipe and openings formed in a surrounding ring, the parts being shown on a scale greatly enlarged as

25 compared with Fig. 1. Fig. 3 is a similar view, showing the joint in its normal position, or with the two pipe sections in actual contact, whereby the openings or passages in the said ring are closed or cut off from 30 communication with the interior of the pipe. Fig. 4 is a cross section of the pipe, taken on the line 4—4 of Fig. 2, looking downwardly.

The same reference characters indicate the same parts in all the views.

35 Let the numeral 5 designate an upright cylindrical tank, whose lower portion is cone-shaped, as shown at 6, the cone-shaped part being surrounded by a casing 7, which is a continuation of the body of the tank 40 above the cone-shaped bottom.

Centrally arranged and suspended within the tank is a standpipe 8, the suspension being accomplished by means of horizontally-arranged braces 9 connecting the wall

45 of the tank with a ring 10, with which the standpipe is equipped, and inclined braces 12, which are connected with the pipe ring 10 at their lower extremities and with an angle bracket 13 at their upper extremities,

50 the angle bracket being secured to the wall of the tank on the inside. These suspension braces or rods 9 and 12 are provided with turn buckles 14, whereby they may be adjusted to produce the required result. The

55 top of the standpipe is further supported by means of screws 15, which are threaded in a cross bar 16, extending across the top of the tank and reinforced by a plate 17, in which is also threaded a screw 18, whose

60 lower extremity is equipped with a baffle plate 19 located a short distance above the top of the standpipe. While these screws 15 serve to suspend the standpipe in its proper central position within the tank, they

65 also are adapted to adjust the movable sec-

tions 20 of the standpipe for the purpose of introducing cross sprays or jets of liquid into the contents of the tank intermediate the extremities of the standpipe. For this purpose, relatively heavy rings 21 are secured to the movable sections 20 by rivets 22, or other suitable fastening devices. In the case of the uppermost section 20, the ring 21 is connected with the lowermost section 20 by means of pins 23, which are made fast to the lower pipe section 20, as shown at 24, the said pins protruding through slots 25 formed in the lower portion of the ring 21, whereby the ring 21, together with the uppermost section 20, may be lifted the length of the slots 25 without moving the lowermost section 20. This lifting operation results in opening a space 26, between the two movable pipe sections and allowing the liquid from the standpipe to issue in jets from the standpipe through passages 27 formed in the ring, which is provided with a reinforcement consisting of a centrally located circumferential rib 28, thus giving the passages 27 sufficient length to 90 properly control the direction of the issuing jets, whereby the said jets have sufficient force to act upon the pulp over the entire cross sectional area of the tank, thus influencing the material falling through the 95 liquid of the tank and producing a perfect separation of the metallic values from the gangue and bringing the dissolving solution of cyanid of potassium into such intimate contact with the metallic values that the said 100 values are quickly dissolved. Now, if it is desired to introduce these cross jets or sprays of liquid into the pulp of the tank at more than one zone, after the uppermost section 20 has been raised to open a space 26 105 between the two sections 20 of the standpipe for the purpose aforesaid, the operation will be continued by imparting a further elevation to the uppermost section 20, in which event, as the pins 23 of the uppermost ring 110 21 are in the bottom of the slots 25, the lowermost section 20, or the section 20 next below the uppermost section, will be lifted until a space 26 is formed between what may be termed the second movable section 20 and the stationary portion 28 of the standpipe 115 below, assuming that the standpipe is equipped with only two movable sections 20. The result will be that the second section 20, together with its ring 21, will be lifted the 120 length of the slots 25 through which the pins 23 pass, thus opening a space between the second section 20 and the lower stationary section of the pipe and allowing the liquid to pass from the pipe outwardly into the tank through the passages 27 with the result heretofore stated. From this, it will be understood that the standpipe may be provided with one or more movable sections, the normal position of the sections being 125 130

such that the openings or passages 27 are closed, it being practicable, however, to place these passages in communication with the interior of the pipe by the vertical movement first of the uppermost movable section, and finally of the section next below, and so on until the desired number of series of jet openings 27 is placed in communication with the interior of the pipe, for the purpose of cross agitation.

The elevation of the pipe sections 20, for the purpose aforesaid, may be accomplished by adjusting the screws 15, heretofore described, the lower extremities of the screws being journaled in ears or lugs 29, secured to the uppermost section 20 for the purpose. It will be understood that as these screws are turned in the proper direction, the uppermost movable section 20 will be lifted until the pins 23 reach the bottom of the slots 25. Then, if the screws are further turned, the second movable section 20 of the standpipe will be raised until the bottoms of the slots 25 engage the pins 23 of the ring 21 next below. When this is done, the two movable sections 20 will be so adjusted as to permit the issuing of jets or sprays of liquid from the standpipe into the surrounding contents of the tank for purposes of additional or cross agitation, as heretofore explained.

As illustrated in the drawing, the upper part of the tank is provided with an interior cylindrical partition 30, which at the top is secured to the cross bar 16, while at the bottom, it is supported upon the angle brackets 13. This partition 30 forms an annular chamber 31, between the upper portion of the wall of the tank and the said partition, this annular chamber 31 forming a quiet or undisturbed compartment for what may be termed the clear solution, from which compartment the said solution may be drawn off through a pipe 32, which extends first outwardly from the tank and then downwardly, communicating with a rotary pump 33, from which the solution is discharged through a pipe 34 into the bottom of the standpipe 8, the inner extremity of the pipe 34 being upturned and protruding into the lower open extremity of the standpipe, as shown at 35. This solution, during the operation of the apparatus, is carried upwardly through the standpipe and discharged at the top thereof, or, more properly speaking, results in producing a circulation of the contents of the tank upwardly through the standpipe and downwardly through the tank in a continuous circuit, the contents of the tank being drawn into the lower extremity of the standpipe and carried upwardly therethrough under the influence of the suction resulting from the discharge of the pipe 34 into the lower extremity of the standpipe. At the same time that

the solution is circulating through the standpipe, intermediately located sprays or jets will be issuing from the standpipe at one or more zones, depending upon the adjustment of the movable sections of the standpipe, as heretofore explained.

Connected with the pipe 34, outside of the tank and between the tank and the centrifugal pump 33, is an upwardly extending relatively small pipe 36, whose upper extremity 75 communicates by way of a horizontal part 37 and a depending part 38 with a circular perforated pipe 39, arranged in a horizontal plane just above or approximately in the same plane with the baffle plate 19.

By virtue of this construction, a portion of the solution issuing from the centrifugal pump and delivered to the pipe 34 is carried upwardly through the pipe 36 and delivered to the perforated pipe 39 from which it issues in the form of sprays or jets into the sheet of solution issuing from the top of the standpipe and thrown in all directions by the baffle plate 19. These sprays or jets produce further cross agitation of the contents of the tank, when taken in connection with the intermediate sprays or jets, producing perfect results of the character desired.

The passage of the solution through the pipe 36 is regulated by a valve 40, it being understood that only a comparatively small portion of the solution is taken up by the pipe 36 and delivered to the perforated pipe located at the top of the tank, as aforesaid.

While my improvements have been illustrated in connection with an apparatus of the general character set forth in the aforesaid patents, and heretofore described somewhat in detail, it is evident that the novel feature of producing cross agitation by the employment of sprays or jets of solution issuing from a standpipe intermediate its extremities and from a perforated pipe suspended in the upper part of the tank, either or both may be employed in connection with any agitating tank having a standpipe through which a circulation of solution is maintained by the introduction of solution at the lower extremity of the standpipe and causing it to discharge at the upper extremity thereof.

Connected with the top of the pipe 32 is a relatively small air pipe 41, whose upper extremity is open whereby, as the solution is drawn through the pipe 32 from the annular chamber 31, air is simultaneously introduced to the solution by the resulting suction. This air pipe is provided with a valve 42, whereby the passage of air therethrough may be controlled.

The lower portion of the pipe 32 is connected with a branch pipe 43, provided with a valve 44. The dissolving solution, also the pulp to be treated, may be introduced to the tank through this pipe. In order to do 130

this, it will only be necessary to open the valve 44 and start the pump 33 in motion. In this event, the valve 40 would be closed. After the treatment of a charge of pulp is completed, and the solid material has settled in the cone-shaped bottom 6 of the tank, this solid material may be removed through an outlet pipe 45 controlled by a valve 46.

Having thus described my invention, what I claim is:—

1. In a pulp agitator, the combination with a pulp-containing tank having an open-ended standpipe, and means for introducing solution into the lower extremity of the pipe whereby the circulation of the pulp through the tank and pipe is established, a portion of the pipe being composed of movable sections and means mounted thereon for introducing liquid jets from the pipe into the surrounding pulp, for the purpose set forth.

2. In a pulp agitator, the combination with a pulp-containing tank having an open-ended standpipe, and means for introducing solution into the lower extremity of the pipe, whereby the circulation of the pulp through the tank and pipe is established, a ring mounted upon the said pipe and having openings which are adapted to be placed in communication with the pipe, for the purpose set forth.

3. In a pulp agitator, the combination with a pulp-containing tank, of an open-ended standpipe suspended in the tank and having a vertically-adjustable section, an exteriorly located ring applied to said section and movably connected with the pipe below the section, the said ring having openings normally closed when the movable section is in its lowermost position, and means for elevating the movable section, whereby a space is formed between the section and the part of the pipe below the section for the escape of the liquid from the pipe through the openings in the ring, substantially as described.

4. The combination with a pulp-containing tank having an open-ended standpipe suspended therein, means for introducing liquid at the bottom of the standpipe, whereby a circulation of the pulp is established through the tank and standpipe, the standpipe having a movable section provided at its lower extremity with a member which surrounds the adjacent part of the pipe, the said member being movable on the pipe below the movable section, the said member having pulp escape openings which are normally closed, and means for raising the movable pipe section whereby the said openings are placed in communication with the liquid in the standpipe, for the purpose set forth.

5. The combination with a pulp-containing tank having an open-ended standpipe suspended therein, and means for introducing liquid at the bottom of the standpipe

whereby a circulation of pulp through the standpipe and tank is established, the standpipe being provided with movable sections whereby the pipe is vertically extensible, the movable sections having openings adapted to be brought into communication with the interior of the pipe when the sections are lifted, and suitable means for raising the movable pipe sections, substantially as described.

6. The combination with a pulp-containing tank, of a standpipe suspended in said tank, means for introducing liquid at the bottom of the pipe whereby a circulation of the pulp is established through the pipe and tank, the pipe having a movable section equipped with a ring secured to the lower extremity of the section and surrounding the upper extremity of the adjacent part of the pipe, the said ring being connected with the upper extremity of the adjacent portion of the pipe to allow a limited vertical movement of the movable section, the said ring having openings which are placed in communication with the pipe when the movable section is lifted, substantially as described.

7. The combination with a pulp-containing tank having an open-ended standpipe suspended therein, means for introducing liquid at the bottom of the standpipe, whereby a circulation of pulp is established through the tank and standpipe, a perforated pipe supported in the upper part of the tank adjacent the upper extremity of the standpipe, and means for introducing liquid under pressure into the said perforated pipe, whereby jets of liquid are delivered by the perforated pipe into the material issuing from the top of the standpipe, the tank being provided with a plate supported above the top of the standpipe, whereby the material is deflected outwardly from the top of the pipe, substantially as described.

8. The combination with a pulp-containing tank, of an open-ended standpipe suspended in the tank, means for introducing liquid into the lower extremity of the pipe whereby a circulation of liquid through the tank and standpipe is produced, the standpipe being equipped with means for introducing jets of liquid into the surrounding pulp of the tank intermediate the extremities of the pipe, and a perforated pipe supported in the tank adjacent the top of the standpipe, and means for introducing liquid under pressure into the perforated pipe, the perforations being arranged to discharge jets downwardly into the pulp of the tank, substantially as described.

9. In a pulp agitator, the combination with a pulp-containing tank having an open-ended sectional standpipe, and means for introducing solution into the lower ex-

tremity of the pipe, whereby the circulation of the pulp through the tank and pipe is established, a ring mounted upon a section of said pipe and having openings which are adapted to be placed in or out of communication with the pipe by means of the vertical movement of said section, substantially as described.

10. The combination with a pulp-agitating tank having an open-ended standpipe suspended therein, means for introducing liquid at the bottom of the standpipe, whereby a circulation of pulp is established through the tank and standpipe, a
15 perforated pipe supported in the upper part of the tank adjacent the upper extremity of the standpipe, and means for introducing liquid under pressure into the said perforated pipe, whereby jets of liquid
20 are delivered by the perforated pipe into

the material issuing from the top of the standpipe, for the purpose set forth.

11. In a pulp agitator, the combination with a pulp-containing tank, having an open-ended standpipe, means for introducing solution into the lower extremity of the pipe whereby the circulation of the pulp through the tank and pipe is established, and means secured to the said pipe, the last-named means being reinforced by a horizontal flange through which perforations extend for introducing liquid jets from the pipe into the surrounding pulp, for the purpose set forth.

25 In testimony whereof I affix my signature in presence of two witnesses.

30 WILLIAM HAMMOND.
